UNITED STATES PATENT OFFICE.

WALTER F. STIMPSON, OF MILAN, MICHIGAN.

DESIGN FOR A SCALE-STANDARD.

SPECIFICATION forming part of Design No. 24,149, dated March 26, 1895.

Application filed September 24, 1894. Serial No. 523,984. Term of patent 14 years.

To all whom it may concern:

Be it known that I, WALTER F. STIMPSON, a citizen of the United States, residing in Milan, Monroe county, and State of Michigan, 5 have invented and produced a certain new and useful Design for Scale-Standards, of which the following is a specification, reference being had therein to the accompanying drawings, forming a part thereof.

10 In the drawings Figure 1 represents a front elevation of a scale standard embodying my design; and Fig. 2 is a side elevation thereof.

The design consists of the cylindrical tapering pillar A, at the top of which is the beaded 15 collar B. From this collar diverge the fanci-

ful inclined scroll shaped arms C having the panelled cross bar D on their upper ends, all as shown in the drawings.

The essential features of the design are the pillar and the fanciful arms thereon connected 20 by the cross bar.

What I claim as new is—

The design for a scale standard, substantially as shown and described.

In testimony whereof I affix my signature 25 in presence of two witnesses.

WALTER F. STIMPSON.

Witnesses:

M. H. HACK,
M. W. BARNES.
